LOCKING SAFETY PIN

Henry Burbig, New York, N. Y.

Application December 8, 1953, Serial No. 396,965

3 Claims. (Cl. 24—156)

This invention relates to a locking type of safety pin. Among the objects of this invention is to provide a safety pin with a locking means which is effective to prevent accidental opening of the pin.

Among other objects of the invention is to provide a safety pin having a flexible locking means mounted thereon which can be easily moved to locking position but which will not be accidentally dislodged to permit opening of the pin.

These and other objects ancillary thereto are obtained by providing a safety pin of an ordinary type which has a head including a keeper means at one end with a flexible elastic sleeve which is slideable along or about the head and into a relatively fixed position on the keeper means so that the said sleeve surrounds the region on the keeper which releasably holds the pointed prong. The head of such safety pins comprises an oval opening and the inside of the elastic sleeve is adapted to slide or move about said opening into a position adjacent the top or back part of the head whereupon the pointed prong can be inserted or removed from the keeper or into a position surrounding a substantial portion of the keeper and the inserted prong so that the said pointed or inserted prong cannot be removed without first moving said sleeve.

The sleeve is made of elastic plastic material so that it stretches to slide along the edge of the head. In most pins the very end of the oval slot in the head is curved so that a sleeve of proper length is in an unstable position at the very end thereof but flattened regions are present parallel to the prongs and keeper so that a properly proportioned sleeve snaps into place at either side of the head. Suitable samples of elastic plastic material for the sleeve include polyvinyl resins, polyethylene, nylon, various synthetic rubbers, plasticized cellulose derivatives such as cellulose acetate and cellulose acetate butyrate, etc. Materials which show at least a small amount of elastic memory such as the vinyl resins have the additional advantage of tightening themselves in locking position after a lapse of time. It is essential that the said sleeve be elastic and of greater flexibility than the metal of which said pin is made.

The invention both as to its organization and its method of operation together with additional objects and advantages thereof will best be understood from the following description of specific embodiments thereof when read in connection with the accompanying drawing in which:

Fig. 1 is a plan view of the pin with the locking means in locked position.

Fig. 2 is a cross-sectional view taken on line 2 of Fig. 1.

Fig. 3 is a view similar to Fig. 1 but showing the head of the pin in cross section.

Fig. 4 is a view of the pin in unlocked and open position.

Fig. 5 is a detail view of a typical locking means.

The pin 10 comprises the loop end 11, the stationary, back rod 12, the pointed prong 13 with end point 14, and the head 20.

2

The head 20 is fixedly held on the curved end 15 of the back rod 12. The head is fixed to the end 15 by being clinched tightly about the end 15 adjacent regions 21, 22. The portion of the head 20 which is spaced from end 15 expands to provide the keeper 23. The interior portion of the head comprises slightly elongated oval shaped slots. This slot generally follows the outside contour of the head but tends to close toward the loop end of the pin. More specifically the slot is generally rounded at the end 25 but has a surface region 26 about a portion of the keeper 23 which is of reduced curvature or even partially flattened. Pins of this type are well known in the art and are manufactured commercially and one advantage of this invention is that the safety or locking element can be combined with an already existing pin.

The locking element 30 is made of relatively flexible plastic material and comprises a ring or sleeve with relatively thick walls which is adapted to fit tightly about a slotted portion of the head 20. The length of the sleeve 30 is approximately equal to or greater than the diameter of the slot 24 at its longest diameter. Under these conditions, the sleeve 30 is always under a slight tension. The position of least strain on the sleeve 30 is that shown in Fig. 4. As the sleeve is pushed around slot 24, in the region of the curved area 25 the sleeve is tensioned due to the forced curving of its axis by the shorter diameter of the slot. As the sleeve 30 is pushed into the locking position of Figs. 1-3 the axis of the sleeve is straightened but the sleeve is expanded due to the greater volume embraced by the keeper 23. Nevertheless, the sleeve snaps into locking position due apparently to the flat surfaces on the outside of the keeper, the flat surface 26 and the positioning of the end of cylinder 30 against the corner where curved surface 25 meets flattened surface 26.

Since the sleeve is slightly expanded when pushed into locking position, the elastic memory of the sleeve operates to tighten the grip thereof about the keeper 23.

The sleeve may be expanded and slipped or forced onto the head of the pin over the keeper portion 23 of the head. If desired the keeper portion may first be sprung slightly out of place to permit the sleeve 30 to be forced thereover and thereafter be forced back into position.

The features and principles underlying the invention described above in connection with specific exemplifications will suggest to those skilled in the art many other modifications thereof. It is accordingly desired that the appended claims shall not be limited to any specific feature or details thereof.

I claim:

1. A locking safety pin comprising a safety pin having a back rod, a pointed prong and a flat head with a rounded external end surface having a thickness slightly greater than the thickness of the back rod attached at one side thereof to the back rod and extending laterally toward said pointed prong which head includes a keeper portion opposite said back rod adapted to releasably hold the pointed prong, the said head portion having an internal rounded slot which generally follows the outside contour of the head but includes a region of reduced curvature adjacent the pointed prong holding part of the keeper portion, in combination with a locking means consisting essentially of a flexible plastic sleeve elastically fitting about the said head so as to slide around the same.

2. The locking safety pin as set forth in claim 1 in which the plastic sleeve is approximately as long as the width of the slot measured transversely of said head portion.

3. In combination, a locking safety pin comprising a safety pin of the type comprising a back rod, a pointed

prong connected to the back rod by a spring element and a head including a hollow keeper portion secured at one side to the free end of said back rod and extending toward said pointed prong, the said head including at least one rounded slot opening in the central region thereof adapted to admit the pointed end of said prong to the hollow keeper portion of the head, said rounded slot including a relatively straight edge portion paralleling the outside of the keeper portion of the head and a locking means consisting essentially of a flexible plastic sleeve of smaller length than the length of said slot and elastically fitting over the region of said head between the slot and the outside surface of the head so as to enclose at least a portion of the slotted region, said plastic sleeve being 15

when surrounding the relatively straight edge portion of said slot thereby being adapted to lock the pointed prong in closed position.
